CLAIM

I claim the ornamental design for a razor cover, as shown and described.

DESCRIPTION

FIG. 1 is a front perspective view of a razor cover, showing my new design, shown in a closed position of use;

FIG. 2 is a back perspective view thereof;

FIG. 3 is a front elevational view thereof;

FIG. 4 is a right elevational view thereof;

FIG. 5 is a left elevational view thereof;

FIG. 6 is a top plan view thereof;

FIG. 7 is a bottom plan view thereof; and,

FIG. 8 is a perspective view thereof shown in an open position of use.

In the drawings, the broken lines illustrate portions of the razor cover that form no part of the claimed design.
